(57) **CLAIM**

The ornamental design for a clothes hanger as shown and described.

DESCRIPTION

FIG. 1 is a front, left and top perspective view of a clothes hanger showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is an enlarged view of portion 9 shown in FIG. 1.

The broken lines are included for the purposes of illustrating portions of the clothes hanger that form no part of the claimed design.
